UNITED STATES PATENT OFFICE.

FREDERIC H. MILLER, OF WILKINSBURG, PENNSYLVANIA, ASSIGNOR TO WESTINGHOUSE ELECTRIC & MANUFACTURING COMPANY, A CORPORATION OF PENNSYLVANIA.

TRANSMISSION-LINE DEVICE.

Application filed October 20, 1927. Serial No. 227,435.

My invention relates to transmission-line devices and particularly to electrostatic-field-control means for high-voltage suspension insulators.

5 One object of my invention is to provide a device of the above-indicated character that shall be protected against damage that might be caused by contact with the line conductor under certain conditions.

15 Another object of my invention is to provide an annular electrostatic-field-control structure that shall permit its installation relative to a transmission-line insulator, while the latter is in operative position between the main supporting base or tower and the line conductor, without necessitating detaching the insulator at any position to receive the annular structure therearound.

Another object of my invention is to provide 20 an electrostatic-field-control device that shall embody relatively movable portions having definitely correlated field-control-surface portions and means for so connecting, and permitting angular movement of, the same as to avoid interference with the field-control function of the surfaces under normal operating conditions.

A further object of my invention is to provide 30 a transmission-line device that shall be simple and durable in construction, economical to manufacture and effective in its operation.

In transmission-line practice, particularly 35 where suspension insulator units are employed, it has been usual to surround the insulator, adjacent to its ends, by field-control or arcing-ring structures.

A recent development in transmission-line 40 practice includes a clamp which, under normal operating conditions, securely grips the conductor, but, in response to breakage of the conductor, is actuated to release the conductor. Particularly, in connection with a clamp of this type, and also, under certain 45 conditions a clamp of any type, by reason of the lateral extent of an arcing ring or shield disposed in parallelism with, and in close proximity to, the line conductor, there are certain conditions under which a portion of 50 the ring or shield and the conductor may engage each other with sufficient force to permanently distort the ring.

Also, where annular one-piece elements, such as rings or discoidal shields, are em-

ployed with high-voltage insulators, unless 55 the rings are installed with the initial installation of the line, the insulators must be detached from the one or the other end to receive the rings.

It is my aim to provide a field-control 60 structure that shall avoid the above-mentioned difficulties and be, in general, an improvement over similar rings heretofore employed.

Accordingly, in practicing my invention, 65 I provide a field-control device embodying portions that move with the conductor when engaged thereby and that may be so constructed as an annular member of relatively movable perimetral or half-sections as to permit its installation around an insulator while the latter is in service.

Figure 1, of the accompanying drawings, 70 is a side elevational view of a transmission-line device embodying my invention, one part being shown, by broken lines, in an alternative position thereof.

Fig. 2 is a top plan view of the structure 75 shown in Fig. 1, except that the insulators are omitted for clearness, and

Figs. 3 and 4 are sectional detail views of 80 the structure, taken along the lines III—III and IV—IV, respectively, of Fig. 1.

Referring to Figs. 1 and 2, the device comprises, in general, a clamp member 2 for the 85 reception of a transmission-line inductor 3, a suspension insulator 4 for supporting the clamp 2 and an electrostatic-field-control device 5 of my invention.

The clamp 2 may be of any usual and well-known type, but, as illustrated, is preferably 90 of the type above-mentioned for permitting the conductor 3 to slip therethrough, under certain abnormal conditions, such as breakage of the conductor between its main supports.

The clamp 2, may comprise a channel member 7, an upper clamping-shoe member 8, a leaf-spring member 9 and a yoke member 10 that is pivotally connected to the channel member 7 by trunnions 12, the latter being 95 supported in alignment with each other, opposite to the conductor 13, by links 14 and a bolt 15.

The specific construction of the clamp 2 which is shown in copending application by N. A. Wahlberg, Serial No. 209,441, filed July 30, 1927, and assigned to the Westinghouse Electric & Manufacturing Company is not

particularly germane to this invention, as claimed, and need, therefore, not be described specifically herein beyond the fact that angular relative movement between the channel member 7 and the yoke 10 releases the spring 9 by a lug (not shown) on the yoke member 10 which cooperates with a cam (not shown). The particular feature of interest in connection with this invention is that, when such action occurs and with the device 5 constructed as such rings are ordinarily constructed, the conductor 3 is likely to engage the field-control device, as heretofore used, with sufficient violence to permanently distort the latter.

In this instance, instead of the field-control device 5 being rigidly mounted, it is constructed so that either the right or the left half of the device, as viewed in the drawing, may move upwardly with the conductor when engaged by it.

To accomplish this result, the device 5 is constructed of half-portions 16 and 17 that are divided along a line at right angles to the direction of the conductor 3. The portions 16 and 17, which have the main field-control surfaces of the device thereon, are provided, on the undersides thereof, with lugs or projections 18, to which arms 20 preferably of strap metal, are secured, as by bolts 21. The arms 20 are pivotally mounted, at the inner ends thereof, on lugs 23, constituting parts of the yoke 10 as by screw pins 24.

The arms 20 are provided with arcuate slots 26 in which the pins 24 are disposed and which are struck about center points 27 in the upper field-controlled surfaces of the structure 5 between the portions 16 and 17.

Similarly, hinge portions or webs 28 and 29, having slots 30 and 31 therein, are secured to the undersides of the portions 16 and 17, respectively, and to each other by pins 32 and 33, in the slots 30 and 31, which provide a lost-motion pivotal connection between the portions 16 and 17 about the points 27.

In the above described structure, since the adjacent inner ends of the halves 16 and 17 of the element 5 and the corresponding ends of the arms 20 are connected by means below the upper main field control surfaces of the element, the connecting or hinge means are shielded by these surfaces and prevented from disturbing the field.

Under normal operating conditions, the parts assume the positions shown in Figs. 2 and 4 and, in full lines in Fig. 1. However, should the conductor 3 and the device 5, by reason of breakage of the conductor or other cause, be moved relative to each other through a sufficient angle about the center of the structure, engagement of the conductor with one of the portions 16 or 17 would cause the latter to be moved away from its normal operating position.

When the conductor 3 and the portion 17, to the right of the center of the structure, as viewed in the drawing, come together, by reason of the lost-motion relation of the pins 24, 32 and 33 to the slots 26, 30 and 31, the elements 17 and 20, at one side of the center of the structure, pivot, as one element, about the point 27 and are automatically returned, by gravity, to their normal operating positions, when the line has been restored to its normal condition. Similarly, the portions 16 and 20, to the left of the center of the device, tilt upwardly about the points 27, when the portion 16 and the conductor 3 engage at that side of the structure.

Since the device 5 is constructed in complementary halves, which are connected by means of the pins 24, 32 and 33, it may be placed together, about the insulator and clamp, and be removed therefrom, while the insulator and clamp are mounted in operative position, without detaching the insulator at either end.

While I have shown and described a particular form of my invention, changes may be made therein without departing from the spirit and scope thereof as set forth in the appended claims.

I claim as my invention:

1. In a transmission-line device, the combination with an insulator, of an electrostatic-field-control structure including a pivotally-mounted field-control portion for displacement by movement of the line conductor. 95
2. In a transmission-line device, the combination with an insulator, of an electrostatic-field-control structure including a field-control portion displaceable and automatically replaceable in accordance with certain movements of the line conductor. 100
3. In a transmission-line device, the combination with an insulator, of an electrostatic-field-control structure including relatively movable half portions for displacement by the line conductor. 105
4. In a transmission-line device, the combination with an insulator, of an electrostatic-field-control structure including angularly relatively movable field-control portions and shielded means for connecting said portions. 110
5. In a transmission-line device, the combination with an insulator, of an electrostatic-field-control structure including relatively movable field-control portions having normally flush field-control conducting surfaces and means shielded by said surfaces for connecting said portions and permitting relative movement thereof. 115
6. In a transmission-line device, the combination with an insulator, of an electrostatic-field-control structure including spaced parallel portions and connecting means permitting corresponding sections of said portions to pivot about a common point in a field-control surface thereof. 120
7. In a transmission-line device, the combination with an insulator, of an electrostatic-field-control structure including spaced parallel portions and connecting means permitting corresponding sections of said portions to pivot about a common point in a field-control surface thereof. 125

7. An electrostatic-field-control device comprising an annular field-control element including relatively movable half portions.
8. An electrostatic-field-control device comprising an annular field-control element including relatively movable half portions and supporting means for each of said portions.
9. An electrostatic-field-control device comprising an annular field control element including relatively movable half portions, supporting means for each of said portions and a single base support for said supporting means.
10. An electrostatic-field-control device comprising an annular field-control element including half portions pivotally relatively movable about a point on the field-control surface thereof.
11. An electrostatic-field-control device comprising an annular field-control element

including half-portions pivotally relatively movable about a point on the field-control surface thereof and supporting means for said portions having lost-motion connection thereto for permitting said relative movement.

12. An electrostatic-field-control device comprising an annular field-control element including half portions pivotally relatively movable about a point on the field-control surface thereof, lost-motion means for connecting said portions and supporting means for said portions having lost-motion connection thereto for permitting said relative movement.

In testimony whereof, I have hereunto subscribed my name this 28th day of September, 1927.

FREDERIC H. MILLER.
